SCREEN PRINTING TABLE FOR PRINTING
ON FABRICS

Gudo Hermen Rodenburg, Helmond, and Gilles Holst, Aalst, near Eindhoven, Netherlands, assignors to N. V. P. F. van Vlissingen & Co.'s Katoenfabrieken, Helmond, Netherlands

Application April 16, 1949, Serial No. 88,018
In the Netherlands April 3, 1948

9 Claims. (Cl. 101—407)

1

The invention relates to a screen printing table, to be used for the execution of so-called screen printing for fabrics.

In the screen printing process, lengths of fabric are laid on very long tables, which might have a length of 90-100 m. On the fabric are laid stencils through which dye is applied to the fabric. An underlayer, e. g. of felt and rubber, generally fabric glued on rubber, is provided on the tables. The drying of the dyed fabric is a problem in such screen printing processes.

Screen printing tables have already been constructed in the form of long, flat, metallic boxes, in which heating tubes are provided, and the heat of the heating tubes must be transferred to the screen top by means of air conduction, which results in great heat losses. Moreover the metal plates forming the screen top can easily expand and/or deform which is very undesirable.

The objects of the present invention are, among others, to overcome the above difficulties.

According to the invention, the screen top consists of massive material, preferably concrete, in which at least one heating tube, preferably having a zig-zag shape, is located in such a way that the material of the screen top bears against the outer surface of the heating tube and surrounds the same.

In this way a very efficient heating of the screen top is obtained.

In order to enable the necessary expansion to take place, the screen top is preferably placed on rollers, which rest on the upper sides of supporting walls.

If the screen top consists of concrete, the heating tube, or tubes, are embedded in the concrete. The screen top can also consist of other material, as e. g. synthetic materials. Preferably material with a small coefficient of expansion will be used to keep contraction and expansion down to a minimum.

As the heat of the heating tubes is not transferred to the screen top through air, but instead is directly transmitted from the tubes, the heating tubes need not be heated to a high degree.

With the construction according to the invention, the preliminary period necessary for the heating of the table surface is quite short. The heating tube, or tubes, can be located in the screen top in such a way that the edges of the screen top, and also the edges of the fabric, are well heated.

The heating tube, or tubes, serve also as a reinforcement for the long tables.

As screen printing tables are generally very

2

long, it is advisable to provide more than one heating tube. If the heating medium should only pass through one long zigzag tube, too much heat would be absorbed at an end of the table. The heating of the table can proceed more uniformly by simultaneously supplying the heating medium at several places along the length of the heating tube in the table.

The problem of heating and drying can be solved in a very efficient way with the apparatus according to the invention, when the screen top provided with the heating tubes is placed on rollers.

The invention is shown more precisely in the accompanying drawing, in which an embodiment is illustrated:

Fig. 1 shows schematically a cross-section through the screen top;

Fig. 2 shows a vertical section through the screen top; and

Fig. 3 shows a transverse section through the table on an enlarged scale.

A heating tube 2 is located in the screen top 1. As appears from Fig. 1 the heating tube is connected with a supply pipe 3. The tube 2 located in the screen top has a zigzag shape, whereas the supply pipe 3 is substantially straight. The heating tube 2 is fed by the supply pipe at the junctions 4, 5 and 6.

In practice the heating tubes are fed preferably with hot water instead of with steam. Consequently a uniform heating is easily obtained, and the temperature can also be maintained at a predetermined level.

As appears from Fig. 2, the screen top is supported by rollers 7, which are placed on the bearing walls 8, e. g. on T-shaped supports 9. In this way spaces 10 are formed between the screen top and the bearing wall. From Fig. 3, it is apparent that the tube 2 can rest on supports 11, which are embedded in the concrete underlayer of the table.

We claim.

1. Screen printing apparatus, comprising in combination, a stationary support; an elongated table top located over said support and being made of a solid material which expands upon being heated; duct means distributed throughout and embedded in the material of said table top for transporting a heating fluid therethrough to heat said table top; and a plurality of mounting means located between said support and table top spaced from each other in longitudinal direction of said table top and extending transversely to the longitudinal direction of the same,

mounting said table top freely movably in its longitudinal direction with respect to said support so as to permit free expansion of said table top when the latter is heated by a heating fluid passing through said duct means.

2. Screen printing apparatus, comprising in combination, a stationary support; an elongated, concrete table top located over said support; duct means distributed throughout and embedded in the concrete of said table top for transporting a heating fluid therethrough to heat said table top; and a plurality of mounting means located between said support and table top spaced from each other in longitudinal direction of said table top and extending transversely to the longitudinal direction of the same, mounting said table top freely movably in its longitudinal direction with respect to said support so as to permit free expansion of said table top when the latter is heated by a heating fluid passing through said duct means.

3. Screen printing apparatus, comprising in combination, a stationary support; an elongated table top located over said support and being made of a solid material which expands upon being heated; duct means distributed throughout and embedded in the material of said table top for transporting a heating fluid therethrough to heat said table top; and roller means located between said support and table top to mount the latter for free movement with respect to said support so as to permit free expansion of said table top when the latter is heated by a heating fluid passing through said duct means.

4. Screen printing apparatus, comprising in combination, a stationary support; an elongated, concrete table top located over said support; duct means distributed throughout and embedded in the concrete of said table top for transporting a heating fluid therethrough to heat said table top; and roller means located between said support and table top to mount the latter for free movement with respect to said support so as to permit free expansion of said table top when the latter is heated by a heating fluid passing through said duct means.

5. Screen printing apparatus, comprising in combination, a stationary support; an elongated table top located over said support and being made of a solid material which expands upon being heated; duct means distributed throughout and embedded in the material of said table top for transporting a heating fluid therethrough to heat said table top, said duct means comprising a plurality of pipe sections connected in parallel with each other so as to heat all parts of said table top simultaneously; and mounting means located between said support and table top to mount the latter for free movement with respect to said support so as to permit free expansion of said table top when the latter is heated by a heating fluid passing through said duct means.

6. Screen printing apparatus, comprising in combination, a stationary support; an elongated, concrete table top located over said support; duct means distributed throughout and embedded in the concrete of said table top for transporting a heating fluid therethrough to heat said table top, said duct means comprising a plurality of pipe sections connected in parallel with each other so as to heat all parts of said table top simultaneously; and roller means located between said support and table top to mount the latter for free movement with respect to said support so as to

permit free expansion of said table top when the latter is heated by a heating fluid passing through said duct means.

7. Screen printing apparatus, comprising in combination, a stationary support; an elongated, concrete table located over said support and having a plurality of metal members embedded therein; duct means distributed throughout and embedded in the concrete of said table top for transporting a heating fluid therethrough to heat said table top, said duct means being at least partially located on said metal members; and roller means located between said support and table top to mount the latter for free movement with respect to said support so as to permit free expansion of said table top when the latter is heated by a heating fluid passing through said duct means.

8. Screen printing apparatus, comprising in combination, a stationary support having a plurality of bearing members located on a top face thereof; an elongated, concrete table located over said support and having a plurality of metal members embedded therein; duct means distributed throughout and embedded in the concrete of said table top for transporting a heating fluid therethrough to heat said table top, said duct means being at least partially located on said metal members; and roller means located between said support and table top to mount the latter for free movement with respect to said support so as to permit free expansion of said table top when the latter is heated by a heating fluid passing through said duct means, said roller means comprising a plurality of rollers supporting said table top and resting on said bearing members, respectively.

9. Screen printing apparatus, comprising in combination, a stationary support having a plurality of bearing members located on a top face thereof; an elongated, concrete table located over said support and having a plurality of metal members embedded therein; duct means distributed throughout and embedded in the concrete of said table top for transporting a heating fluid therethrough to heat said table top, said duct means being at least partially located on said metal members, said duct means comprising a plurality of pipe sections connected in parallel with each other so as to heat all parts of said table top simultaneously; and roller means located between said support and table top to mount the latter for free movement with respect to said support so as to permit free expansion of said table top when the latter is heated by a heating fluid passing through said duct means, said roller means comprising a plurality of rollers supporting said table top and resting on said bearing members, respectively.
